(57) **CLAIM**

The ornamental design for a robotic finger, as shown and described.

DESCRIPTION

FIG. 1 is a front view of a robotic finger showing our new design.

FIG. 2 is a rear view thereof.

FIG. 3 is a right side view thereof.

FIG. 4 is a left side view thereof.

FIG. 5 is a top view thereof.

FIG. 6 is a bottom view thereof.

FIG. 7 is a top-right-front perspective view thereof.

FIG. 8 is a bottom-left-front perspective view thereof.

FIG. 9 is a bottom-left-rear perspective view thereof; and,

FIG. 10 is a top-right-rear perspective view thereof.

The broken line showings of the screw holes, the cutout panel, and the concentric circles are for the purpose of illustrating environmental structure, and the broken lines form no part of the claimed design.

The shade lines show surface contour and not surface ornamentation.
